UNITED STATES PATENT OFFICE.

RICHARD WELLS, OF BALTIMORE, MARYLAND.

APPARATUS FOR STEAMING OYSTERS.

SPECIFICATION forming part of Letters Patent No. 235,189, dated December 7, 1880.
Application filed September 20, 1880. (No model.)

To all whom it may concern:

Be it known that I, RICHARD WELLS, of the city of Baltimore and State of Maryland, have invented certain Improvements in Apparatus for Steaming Oysters in the Shell, of which the following is a specification; and I do hereby declare that in the same is contained a full, clear, and exact description of my said invention, reference being had to the accompanying drawings, and to the letters of reference marked thereon.

My invention relates to certain improvements in that class of apparatus for steaming oysters in the shell in which a steam-tight car having a perforated steam-pipe therein is used for the reception of the oysters, and which car, after being filled, is wheeled on a track to a boiler the steam-space whereof is connected to the perforated steam-pipe aforesaid.

My said invention consists in combining with a series of open-top imperforate cars a suspended top adapted to be lowered upon any one of the said cars to form a tight joint during the steaming operation, the said cars or the removable top being provided with a perforated steam-pipe adapted to be coupled to the flexible end of a stationary steam-pipe leading from a boiler.

The invention further consists in the novel construction of certain parts of the apparatus, as hereinafter set forth.

In the further description of my said invention which follows reference is made to the accompanying drawings, forming a part hereof, and in which—

Figure I is a plan of the apparatus. Fig. II is a longitudinal section of a part of the invention. Figs. III, IV, and V are views of parts of the invention. Figs. VI and VII illustrate a modification in the construction of the apparatus.

Similar letters of reference indicate similar parts in all the views.

A is a track leading from the place where the oysters are landed or stored to a track, B, extending preferably at a right angle therewith, and which is located in the shucking room or compartment. The track B is lower than the one A, in order that the upper surface of a wheeled platform, C, adapted to run

thereon, may be about on a level with the ground upon which the track A is laid.

D is an open-top imperforate wheeled car, a number of which are used in connection with a head or top, E, suspended over any part of the track A by means of suitable hoisting-tackle. The car D is preferably made of iron in the form shown, and it is provided with a coil or gang of perforated steam-pipe, F, and a perforated false bottom, G. One end of the coil or gang projects through the side or end of the car, and is adapted for ready attachment to the flexible end *a* of a steam-pipe, H, leading from a boiler, I. A cock or valve, *b*, is situated at the end of the rigid steam-pipe 65 to control the flow of steam from the boiler. The truck is also fitted with an escape-valve, *c*, for steam and water, located near to the bottom of the vessel.

Parts of the invention not yet alluded to 70 will be described and their uses fully set forth in the description of the operation of steaming oysters by means of my improved apparatus which follows.

A car is filled with oysters in the shell, after which it is wheeled to the position shown in Fig. I of the drawings and the head E lowered thereon. The head E has a gasket, *d*, of rubber or other flexible material, whereby a tight joint between the said head and the edge 80 of the car-body is effected. The flexible end *a* of the steam-pipe H is then attached to the outer end of the steam coil or gang and the cock *b* opened. Steam is thus admitted to the interior of the car and to contact with the oysters. 85 A safety-valve, K, is used to prevent the steam in the car reaching a pressure sufficiently high to lift the head E. After the oysters have been exposed to the action of steam for a proper length of time the cock *b* is closed and 90 the head raised, when the said car is wheeled to the platform C on the track B, and thence to one of the side tracks, L, in the shucking-compartment of the establishment. A newly-loaded truck is now brought under the head 95 E and the oysters therein steamed as before described.

Figs. VI and VII of the drawings show the coil of steam-pipe attached to the head E, instead of being located in the car.

From the foregoing description it will be seen that after a filled car has been subjected to steam it is wheeled entirely out of the way of those to be subsequently connected to the steam-pipe H, and the steaming operation has not therefore to be suspended while the oysters in the first car are being shucked. The flexible end a of the steam-pipe H obviates the necessity of great exactness in the location of the cars when the same are to be connected to the steam-pipe.

I claim as my invention—

An apparatus for steaming oysters in the shell, consisting of an open-top imperforate

wheeled car having therein a perforated steam-pipe, a removable top provided with a gasket and a safety-valve, and adapted for suspension by means of tackle, a track for the wheeled car, a fixed steam-pipe extending from a boiler, and a flexible end to the said steam-pipe, whereby the same and the perforated pipe in the car may be connected, all combined substantially as and for the purpose herein specified.

RICHARD WELLS.
